AIR CLEANER

George N. Clark and Ernest R. Lesage,
Denver, Colo.

Application August 2, 1940, Serial No. 349,559

12 Claims. (Cl. 183—73)

The principal object of this invention is to provide a self-wetting air filter, having numerous pile fibers for contact with the air stream. Generally speaking, this is accomplished by stretching yarn free between spaced upper and lower supports with adjacent strands in substantial contact to form a highly pervious wall that will pass air freely, will catch entrained solids from the air, and will transmit liquid rapidly along the several strands to keep them properly moistened or oiled, as the case may be. Preferably, the yarn is wound up and down about the supports to form a helix or helices, stretched flat and free between the supports to form two walls or a hollow wall, in which the up and down strands are in substantial contact and form a barrier to the passage of any solid matter in the air stream. In many applications, a cylindrical form will be preferred with the supports forming the end portions and held apart by some suitable spacer of open work construction. In others, a flat form will be preferred, but these things lie entirely within the choice of the designer or the customer.

In the drawings, Fig. 1 is a vertical section through one form of the filter diagrammatically connected with an internal combustion engine; connected with an internal combustion engine; connected with an internal combustion engine;

Fig. 2 is a horizontal section on the line 2—2 of Fig. 1;

Fig. 3 is an enlarged fragment of the filter element showing the supports and spacers in section and the yarn in process of being wound about the supports; and

Fig. 4 is a vertical section through an alternative arrangement of filter and casing.

These specific illustrations and the corresponding description are intended for the purpose of disclosure only, and should not be used to impose unnecessary limitations on the claims.

In Fig. 1, there is a base casting 10, having an inlet for air 11 and an outlet 12. In order to interpose the filter proper between the inlet and the outlet, the latter is turned down at 13, and a filter seat 14 is machined to surround the lower end of the outlet. Surrounding this seat and spaced at a considerable distance from it is a casing seat 15 also of circular form, machined on the lower side of the base, and it receives a casing comprising a cylindrical wall 16 and a dished bottom 17 welded to the wall at 18. The dished bottom 17 is welded to the wall at 18. The casing is held in place by a bolt 19 having its upper end screwed into a socket 20 in the base and its lower end equipped with a wing nut 21 bearing against the outside of the dished bottom 17.

The filter element proper, generally indicated by F, and a cylindrical fire screen, generally indicated by S, are assembled between similar sheet metal rings 22 and 23 of channel cross-section, the flanges 24 and 25 thereof cooperating with the respective end portions of the filter and screen, as will appear clearly in Fig. 1.

This sub-assembly is supported by a follower 26 of sheet metal, dished at the middle and provided with a flat flange 27 bearing against the ring 23. A coil spring 28 between the bottom 17 and the follower 26 serves to press the sub-assembly against the filter seat 14 and maintain it in proper position.

The upper side of the follower 26 is provided with a funnel-shaped sheet metal guide 29, welded to it to serve as a guide for the lower end of the bolt 19 as the casing with the sub-assembly is being brought into place with respect to the base 10.

This arrangement is especially suited for internal combustion engines, and, when applied, the outlet 12 will be connected with a carburetor 31 on the engine 32, as indicated diagrammatically at the right of Fig. 1.

The preferred construction of the filter element is shown in Fig. 3, and includes upper and lower supports 33 and 34 in the form of rings of sheet metal, channel-shaped in cross section and having their flanged portions 35 crimped about the respective ends of a cylinder 36 of expanded metal having a thickness much less than the cross section of the supports 33 and 34. This cylinder merely forms a spacer for the supports and is made as open as possible to obstruct the flow of air a minimum.

The actual filtering material is yarn 37 wound lengthwise to the cylinder about the supports 33 and 34 in a sort of helix stretched flat at the inside and the outside to bring adjacent strands substantially parallel and in substantial contact throughout their length as they stretch freely from one support to another. In actual manufacture, it has been found most feasible to wind the yarn in four strands, thus laying up four spirals side by side, or interlaced, but that is purely a matter of choice in manufacturing and does not materially affect the operation of the filter.

It is particularly desirable that the strands of yarn hang free from one support to the other, for the travel of the liquid up or down the yarn would be obstructed if there were any contact with the spacing cylinder 36. It is also prefer-

able not to have any transverse yarn for the same reason.

In practice, it has been found that four-stranded wool yarn, having 74 yards per ounce, is very satisfactory for filters to be used with internal combustion engines either at the intake or at the breather. This yarn has very extensive pile fibers and when laid up as described presents a pile surface that bars all solid matter from passage with the air while being itself extremely pervious to the air and offering a minimum of resistance to the flow.

The fire screen is a fine wire netting to prevent a back-fire from the carburetor setting fire to the oiled yarn.

It has been found good practice to solder the ends of the fire screen to the flange 25 of each of the rings 22 and 23, making the sub-assembly stay intact, whereby, when the unit is being handled, the yarn is not damaged by being cut or bruised when the support is brought into contact with metal objects or cement floors as are commonly used in garages.

In the assembly shown in Fig. 1, a small amount of oil is put in the bottom of the casing to wet the lower ends of the yarn strands, which by capillary attraction quickly feed the oil upwardly and maintain the whole in uniformly wetted condition. Within the casing and welded to the bottom 17 is an overflow pipe 38, which limits the upper level of the oil in the casing.

When the filter is used to introduce a liquid into a gas stream, the liquid will be supplied either from the bottom or from the top and will be quickly fed along the parallel strands, and the filter will be kept uniformly wetted from top to bottom.

In Fig. 4 is an alternative arrangement for internal combustion engines including an inlet casing 39 and an outlet casing 40 spaced apart with the filter element 41 and the screen cylinder 42 arranged between them substantially as shown. The inlet casing has a liquid chamber 43 closed at the top by a filling plug 44 and having feed openings 45 in the bottom to feed the liquid to the yarn in the filter element 41.

The outlet casing has a liquid receptacle 45, the bottom of which is in contact with the closure element and the screen 42. Within the screen, the outlet casing includes a tube or pipe 46 to be connected with the carburetor of the internal combustion engine. The inlet casing includes a flange 47, slightly larger than the receptacle 45 of the outlet casing, and serves to form with that casing an inlet for the air to the outside of the filter element. The length of the flange 47 will be varied by designs, and the choice is indicated by the dotted lines in Fig. 4.

The connection between the inlet and outlet casings and the spacing for the supports of the filter element have been omitted in the interest of clearness.

Various other forms could be readily designed to suit individual preferences and particular conditions.

After a suitable period of operation, the filter yarn will become more or less clogged with solid matter, but can be readily cleaned by washing in any suitable solvent, such as gasoline or other higher volatile for filters used in gasoline engines, and kerosene or 300 degree oil for filters used in Diesel engines.

The operation is simple. The wing nut 21 is taken off in the form shown in Figs. 1 and 2, and the casing with the filter unit removed by

pulling down. Then the filter can be put in a suitable container and washed, and, after, reassembled as shown.

We claim:

5. In a device of the class described, spaced circular ring supports, one above the other, spacing means between said supports and forming therewith a skeleton cylinder, and yarn wrapped about the supports to form upwardly extending circular concentric walls of strands that are substantially parallel, the strands of each wall being in contact.
10. In a device of the class described, a casing having an inlet and an outlet for air, a filter between the inlet and the outlet including upper and lower circular ring supports and spacing means overhung both inside and outside by said ring supports and forming therewith a skeleton cylinder, and yarn wound about the supports to form inner and outer yarn cylinders with adjacent strands in contact for substantially their entire lengths, said cylinder walls being spaced apart by the thickness of said ring supports and the inner wall of the outer yarn cylinder and the outer wall of the inner yarn cylinder being spaced from said spacing means.
15. In a device of the class described, spaced circular ring supports, one above the other, spacing means between said supports and forming therewith a skeleton cylinder, and yarn wrapped about the supports and forming two concentric yarn cylinders having the same number of yarn elements which are substantially parallel and with adjacent strands in substantial contact for their entire lengths, the inner yarn cylinder because of its smaller diameter having its strands slightly closer together than are the strands of the outer yarn cylinder.
20. In a device of the class described, spaced circular ring supports, one above the other, spacing means between said supports and forming therewith a skeleton cylinder, and yarn wrapped about the supports and forming two concentric yarn cylinders having the same number of yarn elements which are substantially parallel and with adjacent strands in substantial contact for their entire lengths, the inner yarn cylinder because of its smaller diameter having its strands slightly closer together than are the strands of the outer yarn cylinder.
25. In a device of the class described, a casing having an inlet and an outlet for air, a filter between the inlet and the outlet, composed of more open and less open sections in series, both of said sections being composed of substantially parallel stretched strands of yarn the strands of said yarn being of the same cross-sectional area, and each strand being in contact with the adjacent strands, the less open section having its adjacent yarn strands in a closer contact than the adjacent strands of the more open section.
30. In a device of the class described, a casing having an inlet and an outlet for air, a filter between the inlet and the outlet, composed of substantially parallel stretched strands of yarn the strands of said yarn being of the same cross-sectional area, and each strand being in contact with the adjacent strands, the less open section having its adjacent yarn strands in a closer contact than the adjacent strands of the more open section.
35. In a device of the class described, a casing having an inlet and an outlet for air, a filter between the inlet and the outlet, composed of substantially parallel stretched strands of yarn the strands of said yarn being of the same cross-sectional area, and each strand being in contact with the adjacent strands, the less open section having its adjacent yarn strands in a closer contact than the adjacent strands of the more open section.
40. In a device of the class described, a casing having an inlet and an outlet for air, a filter between the inlet and the outlet, composed of more open and less open sections in series, both of said sections being composed of substantially parallel stretched strands of yarn the strands of said yarn being of the same cross-sectional area, and each strand being in contact with the adjacent strands, the less open section having its adjacent yarn strands in a closer contact than the adjacent strands of the more open section.
45. In a device of the class described, a casing having an inlet and an outlet for air, a filter between the inlet and the outlet, composed of substantially parallel stretched strands of yarn the strands of said yarn being of the same cross-sectional area, and each strand being in contact with the adjacent strands, the less open section having its adjacent yarn strands in a closer contact than the adjacent strands of the more open section.
50. In a device of the class described, a casing having an inlet and an outlet for air, a filter between the inlet and the outlet, composed of substantially parallel stretched strands of yarn the strands of said yarn being of the same cross-sectional area, and each strand being in contact with the adjacent strands, the less open section having its adjacent yarn strands in a closer contact than the adjacent strands of the more open section.
55. In a device of the class described, a casing having an inlet and an outlet for air, a filter between the inlet and the outlet, composed of substantially parallel stretched strands of yarn the strands of said yarn being of the same cross-sectional area, and each strand being in contact with the adjacent strands, the less open section having its adjacent yarn strands in a closer contact than the adjacent strands of the more open section.
60. In a device of the class described, spaced circular ring supports, one above the other, spacing means between said supports and forming therewith a skeleton cylinder, and yarn wrapped about the supports and forming two concentric yarn cylinders of the same number of strands and of the same thickness whose yarn elements are substantially parallel and with adjacent strands in substantial contact for their entire lengths.
65. In a device of the class described, spaced circular ring supports, one above the other, spacing means between said supports and forming therewith a skeleton cylinder, and strands of yarn stretched between the supports to form a circular wall of substantially parallel contacting strands side by side and spaced outwardly from said skeleton cylinder and another cylinder wall
70. In a device of the class described, spaced circular ring supports, one above the other, spacing means between said supports and forming therewith a skeleton cylinder, and strands of yarn stretched between the supports to form a circular wall of substantially parallel contacting strands side by side and spaced outwardly from said skeleton cylinder and another cylinder wall

of substantially parallel contacting strands side by side spaced inwardly from said skeleton cylinder and spaced from said first-named strands.

8. In a device of the class described, a casing having an inlet and an outlet for air, a filter between the inlet and the outlet including upper and lower circular ring supports with spacing means therebetween, and yarn stretched between the supports to form two concentric circular walls of strands side by side in substantial contact, and means including a reservoir for containing a liquid into which the lower portions of said strands extend for supplying a liquid to the yarn.

9. In a device of the class described, a casing having an inlet and an outlet for air, a filter between the inlet and outlet including upper and lower circular ring supports and spacing means overhung both inside and outside by said ring supports and forming therewith a skeleton cylinder, and yarn wound about the supports to form inner and outer yarn cylinders with adjacent strands extending vertically in contact for substantially their entire length, said cylinder walls being spaced apart by the thickness of said ring supports whereby each yarn cylinder clears said spacing means, and means to supply a liquid to said yarn by capillary attraction only.

10. In a device of the class described, a casing having an inlet and an outlet for air adjacent its upper end, a filter between the inlet and the outlet including upper and lower circular ring supports with spacing means therebetween and yarn stretched between the supports to form two concentric circular walls of strands spaced apart, the strands of each wall being side by side in substantial contact for their entire lengths, the outer wall having its upper end inwardly of and adjacent the outlet, whereby the more closely

spaced strands of the inner wall will filter out any material that may pass through the more loosely spaced strands of the outer wall.

11. In a device of the class described, spaced circular supports one above the other, spacing means between said supports and forming therewith a skeleton cylinder, and strands of combustible yarn stretched between the supports to form a circular wall of substantially parallel strands side by side outside the said circular supports and another circular wall of substantially parallel strands side by side inside of said circular supports, whereby said inner yarn wall will be closer built and will filter out any material that may have passed through the outer yarn cylinder wall, and a metallic screen adjacent the inner yarn cylinder wall to prevent the inward passage of broken pieces of said yarn and to prevent the burning of said yarn walls through backfires.

12. In an air cleaner for internal combustion engines, the combination of a casing having an inlet and an outlet for air, a filter between the inlet and the outlet, said filter comprising more open and less open sections in series, both of said sections being composed of substantially parallel stretched strands of yarn, the less open section having adjacent yarn strands in closer contact than the adjacent strands of the more open section, and metallic screen means in series with said two sections of said filter to prevent the passage of foreign matter from said filter to said engine and to prevent combustion of said filter through backfires, said less open section being between the screen and the more open section and said screen being arranged inwardly of said sections.

GEORGE N. CLARK.
